Specification of Letters Patent. Patented Dec. 18, 1917.

Application filed May 19, 1915. Serial No. 29,034.

To all whom it may concern:

Be it known that I, JOHN C. McLAUGHLIN, a citizen of the United States, residing in East Orange, in the county of Essex and 5 State of New Jersey, have invented certain new and useful Improvements in Type-Writing Machines, of which the following is a specification.

The present invention relates to mechanism for vibrating the ribbon of a typewriting machine to cause it, at each type stroke, to cover the printing point at the platen, and after the type stroke, to return to a normal position in which the printing point is 10 uncovered. More particularly, the invention relates to ribbon vibrating mechanism adapted for use with a so-called bichrome or multi-color ribbon, that is to say, one which has distinct bands or zones of inks 15 of different color arranged one beyond another. The use of a bichrome ribbon ordinarily involves the use, in connection with the ribbon vibrator, of means for giving it any one of a plurality of settings, so that 20 the throw of the ribbon may be varied according to which of the color bands is selected.

One of the objects of the present invention is an improved mechanism for effecting and changing the settings of the vibrator; the parts thereof being of simple and durable construction, and of such design as to be capable of being compactly assembled.

Most typewriting machines have a case 35 shift, the platen being ordinarily shiftable between upper and lower case positions. The ribbon vibrator must be accommodated to this shift.

An object of the present invention is an 40 improved support and mounting for the vibrator, and for the actuating and setting mechanisms of the latter, in combination with novel means for shifting the support with the platen to maintain proper relation 45 between the ribbon and the platen.

The invention is particularly designed for use in a machine of the kind in which the ribbon vibrator is actuated from a universal bar, which, in turn, is actuated by whatever 50 type-bar is struck. Owing to the fact that the type-bars ordinarily do not actuate the universal bar until they have moved well on their way to the platen, there is little

time for the universal bar to throw the ribbon to the printing point. The movement 55 of the vibrator must therefore be extremely rapid, and yet the momentum gathered by such rapidity of movement must not be allowed to overthrow the ribbon. These requirements are answered by employing a 60 toggle as an actuator of the vibrator, intermediate the universal bar and the vibrator; the speed of drive of the vibrator being gradually decreased as the toggle straightens out, and the ribbon nears the printing 65 point.

Toggles for this purpose are not broadly new. It is an object of the present invention, however, to provide an improved form 70 of shiftable connection between the toggle and the vibrator, such that, although no change be made in the connection of the toggle to the universal bar, the throw of the vibrator may nevertheless be varied for the different ribbon zones selected, and the 75 vibrator silenced at will when stenciling is to be effected. In one of the preferred forms of the present invention, the adjustable connection of the toggle to the vibrator is shown as a lever having a slot so disposed therein 80 that one of the toggle arms may be attached thereto at distances nearer to or farther from the pivot of the vibrator lever according to the desired throw of the vibrator; and having a second slot in which the toggle arms may be set to move freely without 85 actuating the lever when stenciling is to be effected.

A feature of the invention concerns a means whereby the movement of the universal bar with the vibrator is normally positively arrested to prevent overthrow of the ribbon, but which may nevertheless, when the occasion requires, be made to permit an abnormal movement of the universal bar to permit removal of type-bars. In attaining this object of the invention, an improved holder is provided for the toggle support, such that, although this support is normally shiftable only between case positions, it may, upon being in part released by the holder, be capable of an abnormal movement with the universal bar.

Other features and advantages will hereinafter appear.

Figure 1 is a fragmentary view, in front

elevation, of the ribbon vibrating and setting mechanism, shown in conjunction with the platen, the parts being set with the red ribbon operative.

5 Fig. 2 is a sectional side elevation of the machine, the parts being in the same position as in Fig. 1.

10 Fig. 3 is a view in side sectional elevation, showing the mechanism, in conjunction with the platen and a type-bar, in the position assumed in printing black in lower case.

15 Fig. 4 is a view similar to that of Fig. 3, except that the setting of the parts is such that red is being printed in lower case.

20 Fig. 5 is a view similar to Figs. 3 and 4, with the parts set to print black in upper case.

25 Fig. 6 is a view similar to Figs. 3, 4 and 5, with the parts set to print red in upper case.

30 Fig. 7 shows, in perspective, and disconnected, the actuating and setting parts for the ribbon vibrator.

35 Fig. 8 is a view, in sectional side elevation, similar to that of Fig. 3, except that the view is taken from the left-hand side of the machine, and the parts are in stenciling position.

40 Fig. 9 is a perspective view of the mechanism shown in Fig. 1.

45 Referring to the drawings, and more particularly to Fig. 2, the platen 1 is shown as journaled in platen frame 2, mounted on the carriage 3 and shiftable up and down thereon to bring the platen to upper and lower case positions. A roller 4 on the platen frame runs on a shift rail 5, carried on a frame 5^a, adapted to be swung up around a pivot 5^b, by shift-key levers, operated by the usual shift key 5^d. The type bars 6 are actuated by keys 8 on the key levers 9 connected to the type-bars through bell cranks having pins 7 working in slots in the type-bars to swing the latter about their fulcrums, so that depression of a key 8 throws the connected type bar upward and rearward to cause a type 10 to strike against the front face of the platen.

50 The carriage may be driven by the usual spring drum (not shown); and the letter-feed movement of the carriage is controlled by escapement mechanism comprising a dog-rocker 11, and an escapement wheel 12, which dogs 13, on the rocker, engage. A pinion 14, connected to drive the escapement wheel 12 during the letter-feed travel of the carriage, runs in mesh with a rack 15 on the carriage. A universal bar 16 lies in the path of shoulders 17 on the type-bars 6, and at each type stroke, a shoulder 17 strikes the universal bar as the type approaches the printing point and moves the universal bar rearward, thereby causing a rearward extension 18 of the universal bar 65 to strike and operate the dog-rocker 11. At

the rear of the universal bar, the ends thereof are pivotally connected, as at 19, to arms 20 which swing on a rod 21, mounted in the frame, thus supporting and guiding the bar in its movements. Forward, the bar is also supported by, and slides on, the type segment. The bar therefore moves easily and with the same movement for all type strokes. It cannot be twisted or distorted by the strokes of outlying type-bars adjacent its ends; and in actuating the escapement mechanism and the ribbon-vibrating mechanism, as hereinafter to be described, its movements are reliable and uniform for all type-bars.

80 The ribbon - vibrating mechanism (see more particularly Fig. 4) comprises a ribbon vibrator and guide 23 through which the ribbon 24 is threaded, and by which it is vibrated over the printing point at each type stroke. The ribbon preferably comprises a plurality of color bands or zones for printing in different colors, and, as shown, comprises an upper black band 26 and a lower red band 27. The vibrator is actuated by a vibrator lever 28 to which it has a hook-and-pin connection 29. The lever 28 is pivoted at 30, by means of a pin 34, to a plate 31. The plate 31 (see Figs. 7 and 9) at its front edge, fits within a way 32 in the frame 33. Its rear edge lies in a guideway 32^a, which, however, is not closed at the rear, in order that for certain purposes later to be mentioned and relating to the assembling of the machine, the plate 31 may be swung out through the guideway 32^a. Normally, however, a plate 35, pivoted to the frame at 36, is held by a coil spring 37 in such position as to close the rear of the guideway 32^a, thus preventing any but a sliding up-and-down movement of the plate 31 in its ways. The purpose of permitting the plate 31 to have such movement is that it may be shifted with the platen between case positions. To effect this up-and-down shift of the plate 31, the pin 34, which connects the lever 28 to the plate, also connects the plate to the end of a lever 35, the other end of which is pivotally connected, at 36, to the type segment. Carried by this lever 35, at an intermediate point 37 thereof, is a pin 38, held in a slot 39 in a bracket 40, secured to and depending from the shift rail 5. When, therefore, the platen and with it the bracket 40, is lifted or lowered, the lever 35 is rocked about its pivot 36, and the plate 31 with its connected parts correspondingly lifted or lowered. Slot 39 allows for the necessary play of the pin 38 as the lever swings.

125 The vibrator lever 28 is actuated at each type stroke, that is to say, whenever the ribbon is to be used. In stenciling, since the ribbon is not desired, the vibrator is silenced in a manner presently to be described. The 130

vibrator when in use is set to present either the black or the red band to the printing point. To so present the red or lower band, necessitates a greater throw of the vibrator than is required when the black or upper band is used. Consequently, provision is made for two settings of the vibrator actuator. This actuator consists of a toggle having two links or arms 41 and 42, pivotally connected at 43. The lower arm 41 is pivoted at 44 to the plate 31 near the foot of the latter, so that the toggle as a whole moves with the plate 31 between case positions. The upper arm 42 of the toggle carries a pin 45 which passes through a slot 46 in the vibrator lever 28, and beyond the latter is engaged in a fork 47 in a setting plate or arm 48. The plate 48 is mounted to swing about the point 44 on the plate 31 as a pivot, and the same pin 49 which serves to pivot the toggle arm 41 to the plate 31, may serve as the pivot of the plate 48.

According to the set position of the pin 45 in slot 46, the toggle will give the vibrator lever, and with it the ribbon, a longer or shorter throw when the toggle is actuated at type strokes. The setting of the pin 45 in the slot 46 is determined by the angular position of the plate 48; and the position of the plate 48 is in turn controlled by the following means: A rock shaft 50, supported at one end, at 51, in the toggle-supporting plate 31, passes through a slot 52 in the setting arm or plate 48. The slot 52 is curved in the arc of a circle struck from 44 as a center, so that the plate 48 may swing without interfering with the shaft 50. Beyond the plate 48 the shaft 50 has a U-shaped bend 53, which acts as an arm and is loosely held between two ears 54 on the plate 48. When the shaft is rocked, the bend 53 therein engages one of the ears 54 and moves the plate 48 to set the toggle. The other end of the shaft is held in a bracket 55 on the machine frame, by a collar 56. Its support in the bracket 55 is, however, sufficiently loose to permit its other end, at 51, to be raised and lowered with the toggle plate 31 in case-shifting.

Fixed to the rock shaft 50 is an arm 57, connected by a link 58 to an arm 59 fast on a second rock shaft 60. The shaft 60, at the front of the machine, carries on either side thereof, an arm 61, on which keys 62 and 63, respectively, are mounted. When the keys are equally elevated, the position of the shafts 60 and 50 and of plate 48 is such that the pin 45 on the toggle is about central of the slot 46 in the vibrator-lever 28, as shown in Fig. 3. If when the pin 45 is held in this position, the toggle is actuated, the throw of the vibrator lever will be such as to bring the upper or black ribbon band to the printing point. A depression of the key 63 at this time will move the shafts 60 and 50 and

plate 48, to throw the toggle pin 45 to the end of the slot 46, as shown in Fig. 4, in which position it is nearer the pivot 30 of lever 28, and will, therefore, upon actuation of the toggle throw the ribbon farther than 70 when in Fig. 3 position. This greater throw is the throw required to present the red ribbon band to the printing point.

Since, in stenciling, no throw of the ribbon is desired, there remains to be described 75 one other adjustment of the toggle pin 45. It will be noted on reference to the drawings, that the slot 46 has, leading from one end thereof at approximately a right angle thereto, a slot 65. If the toggle pin 45 be 80 brought to that end of slot 46, and the toggle thereupon actuated, the pin 45 merely moves in the slot 65 without actuating the vibrator lever. This, which is the stenciling position of the toggle, is effected by still 85 another movement of the key shaft 60. Fast to one of the key-carrying arms 61 is a pin 66. During the movement of the keys 62 and 63, between Fig. 3 and Fig. 4 positions, the pin 66 moves in a slot 67 in a plate 68, 90 and the ends of slot 67 may serve as stops to determine the throw of the keys and connected parts. The plate 68 is pivoted to the machine frame at 69. It carries a finger-piece 70 by means of which it may be moved 95 about its pivot, and a spring detent 71 by means of which it may be held against displacement by co-operation with notches 72 and 73 in a fixed bar. Normally the plate 68 is in Fig. 1 position. 100

When stenciling is to be done, plate 68 is swung back until detent 71 engages notch 73. This movement of the plate 68 causes the pin 66 to move across the slot 67, and, on striking the other side wall thereof, to be cammed by the latter into a branch slot 75, and to be forced down this branch slot until it rides onto a dwell 76 at the end thereof. In thus forcing the pin 66 down the slot 75, the shaft 60 is moved to bring the toggle pin 45 to 105 Fig. 9 position, for movement in the slot 65 in the vibrator lever. The dwell 76 locks the keys and shaft 60 against movement until the plate 68 is returned to normal position. On return of plate 68 to normal position, the pin 66 is cammed to the upper end of its slot, thereby bringing the keys and connected parts to black ribbon position, no matter from what position they may have been thrown on the movement to stenciling 110 position. 115

It remains to describe the actuation of the ribbon vibrator from the universal bar at the type strokes. Secured to the under side of the universal bar is a depending 120 bracket or slotted ear 77. The slot 78 in this ear is vertical and engages an extended portion of the pivot pin 43, which connects the arms 41 and 42 of the toggle. Forward and backward movement of this slotted ear 125 130

with the universal bar therefore collapses and straightens out the toggle to give the vibrator lever its throw. The length of the slot 78 is not only sufficient for the up and down 5 play of the toggle joint, but is sufficient to permit the toggle to be moved between case positions and to be operable in either position.

A stop 80 in the form of an overturned 10 ear on the toggle-setting plate 48, by engagement with the vibrator lever 28, positively determines the throw of the ribbon, and prevents overthrow of the latter. When the plate 48 has been swung to a position to set 15 the toggle for the black ribbon printing, the stop 80, as shown in Figs. 3 and 5, is in line with, and engages a lug 81 on the vibrator lever; but when the setting is for the red ribbon, the stop (see Figs. 4 and 6) is 20 rearward of the lug 81 and arrests the vibrator lever 28 by direct engagement therewith.

In connection with the description of the mounting of the toggle support 31, reference was made to the fact that the guideway 32^a 25 therefor was in part formed by a pivoted plate 85, so that at times the support 31 could be swung rearwardly around its pivot 30. The purpose of such a swing of plate 31 is to permit the type-bars to be removed from, 30 or placed in, the type segment. It is usual in typewriting machines to support the universal bar on the type segment over the points of attachment to the latter of the type-bars. Ordinarily, when a type-bar is 35 to be placed or removed it is simply necessary to throw back the universal bar sufficiently to uncover the type-bar attachments.

In the present invention, however, the rearward movement of the universal bar is 40 normally limited, and is determined by engagement of the vibrator lever 28 with the stop 80 on the setting plate 48. This normal movement may not be sufficient to permit removal of the type-bars, and therefore the 45 following means is provided to permit of an abnormal movement of the universal bar when desired.

Since it is indirectly the toggle support 50 31 which normally arrests the movement of the universal bar when the vibrator lever 28 contacts with stop 80, it is apparent that by releasing the support 31 to a swinging movement around its pivot 30, an additional throw of the universal bar may be obtained. 55 This release of the toggle support is effected by a removal of the plate 85, which normally obstructs the rear of the guideway 32^a. To remove the plate 85, it is merely 60 swung by a finger-piece 88 around its pivot 86. Such a movement of the plate 85 forces the edge thereof against a cam face 89 on an arm which is rigidly attached to the pivot rod 21 of the universal bar, and thus causes 65 the universal bar to be given an abnormal rearward throw, and through its connection

with the toggle on a vibrator support, simultaneously to swing the latter rearwardly through the guideway 32^a, previously obstructed by the plate 85. While plate 85 is held in this position, type-bars may be removed. On release of the plate 85, its spring 70 87 returns it to normal position, determined by a stop 90, which the plate strikes on its return movement. A cam 91 on the plate 85 strikes and returns the toggle support 75 31 to normal position during the return movement of the plate 85. The usual spring (not shown) throws forward the universal bar.

Variations may be resorted to within the 80 scope of the invention, and portions of the improvements may be used without others.

Having thus described my invention, I claim:

1. In a typewriting machine; type keys; 85 a ribbon vibrator; means for actuating the vibrator from the type keys, said actuating means comprising a vibrator lever and a toggle connected directly to said lever; and means for shifting the point of connection 90 of the toggle toward and from the fulcrum of the lever to vary the throw of the vibrator.

2. In a typewriting machine; type keys; 95 a ribbon vibrator; means for actuating the vibrator from the type keys, said actuating means comprising a lever connected to the vibrator, a toggle connected at one end to said lever; a support to which the other end of the toggle is pivoted; and means for shifting the point of connection of the toggle to the lever toward and from the fulcrum of the lever to vary the throw of the latter without changing the connection of the vibrator to said support. 100

3. In a typewriting machine; type keys; 105 a ribbon vibrator; means for actuating the vibrator from the type keys, said actuating means comprising a lever connected to the vibrator; a toggle having a pin - and - slot 110 connection to said lever; and means for shifting the position of the pin in the slot to vary the throw of the lever.

4. In a typewriting machine; type keys; 115 a ribbon vibrator; means for actuating the vibrator from the type keys, said actuating means comprising a connection to said vibrator, a toggle having a pin-and-slot attachment to said connection; and means for shifting the position of the pin in the slot 120 to vary the throw of the vibrator.

5. In a typewriting machine; type keys; 125 a ribbon vibrator; means for actuating the vibrator from the type keys, said actuating means comprising a toggle connected to said vibrator; mechanism for shifting the point of connection of the toggle to the vibrator to vary the throw of the latter; and means co-operating with said mechanism to render said connection inoperative at will. 130

6. In a typewriting machine; type keys; a ribbon vibrator; means for actuating the vibrator from the type keys, said actuating means comprising a lever connected to the vibrator, said lever having a slot therein from a point nearer its pivot to a point more remote therefrom, and a second connecting slot at an angle thereto; and a toggle having a pin settable at a position in said first-named slot to actuate said lever from the toggle and settable at another position in said first-named slot, where, upon actuation of the toggle, the pin will move freely in said second-named slot, without actuating the lever. 10
7. In a typewriting machine; type keys; a ribbon vibrator; means for actuating the vibrator from the type keys, said actuating means comprising a lever connected to the vibrator, said lever having a slot therein from a point nearer its pivot to a point more remote therefrom, and a second connecting slot at an angle thereto; a toggle having a pin in said first-named slot to actuate said lever from the toggle; and means for setting the pin at different positions in said first-named slot to vary the throw of the lever, and for setting the pin at another position in said first-named slot where, upon actuation of the toggle, the pin will move freely in said second-named slot without actuating the lever. 20
8. In a typewriting machine; type keys; a ribbon vibrator; means for actuating the vibrator from the type keys, said actuating means comprising a lever connected to the vibrator, said lever having a slot therein from a point nearer its pivot to a point more remote therefrom, and a second connecting slot at an angle thereto; a toggle having a pin in said first-named slot to actuate said lever from the toggle; means for setting the pin at different positions in said first-named slot to vary the throw of the lever, and for setting the pin at another position in said first-named slot where, upon actuation of the toggle, the pin will move freely in said second-named slot without actuating the lever, said setting means comprising a key connection for shifting the pin to said last-named position; and means whereby said connection is automatically locked against displacement when the pin is so shifted. 40
9. In a typewriting machine; type keys; a ribbon vibrator; means for actuating the vibrator from the type keys, said actuating means comprising a lever connected to the vibrator, said lever having a slot therein from a point nearer its pivot to a point more remote therefrom, and a second connecting slot at an angle thereto; a toggle having a pin in said first-named slot to actuate said lever from the toggle; and means for setting the pin at different positions in 50
- said first-named slot to vary the throw of the lever, and for setting the pin at another position in said first-named slot where, upon actuation of the toggle, the pin will move freely in said second-named slot without actuating the lever, said setting means comprising a key lever, and a cam for actuating the same, said cam having a dwell therein which when engaged by the key lever, locks the latter against displacement. 75
10. In a typewriting machine; type keys; a ribbon vibrator; means for actuating the vibrator from the type keys, said actuating means comprising a lever connected to the vibrator, said lever having a slot therein from a point nearer its pivot to a point more remote therefrom, and a second connecting slot at an angle thereto; a toggle having a pin in said first-named slot to actuate said lever from the toggle; means for setting the pin at different positions in said first-named slot to vary the throw of the lever, and for setting the pin at another position in said first-named slot where, upon actuation of the toggle, the pin will move freely in said second-named slot without actuating the lever, said setting means comprising a key lever, and a key thereon for moving the key lever in one direction to set the toggle pin for a different throw of the vibrator lever; and means for moving the key lever farther in the same direction to bring the toggle pin to a position where it will not operate the vibrator lever. 80
11. In a typewriting machine; type keys; a ribbon vibrator; an actuator for actuating the vibrator; a key having a normal range of movement; means operated by the key during such movement to change the point of connection of the actuator to the vibrator to vary the throw of the latter; and a cam for moving the key in one direction beyond said normal range, and thereby operative through said means to render inoperative the connection of said actuator to the vibrator. 100
12. In a typewriting machine; type keys; a ribbon vibrator; means for actuating the vibrator; a key having a normal range of movement; means operated by the key during such movement to change the point of connection of the actuator to the vibrator to vary the throw of the latter; and a cam for moving the key in one direction beyond said normal range and thereby operative through said means to render inoperative the connection of said actuator to the vibrator, said cam having a dwell therein whereby it automatically locks said vibrator connection in its inoperative position. 115
13. In a typewriting machine; type keys; a ribbon vibrator; means for actuating the vibrator; a key; means actuated by the key when moved in one direction to change the position of the actuator to vary the throw 120
- 65 125
- 130

- of the vibrator, and a cam arranged to move the key farther in the same direction and thereby render the actuator inoperative. 65
14. In a typewriting machine; type keys; a ribbon vibrator; means for actuating the vibrator; a key; setting means actuated by the key when moved in one direction to change the position of the actuator to vary the throw of the vibrator, a cam arranged to move the key farther in the same direction and thereby render the actuator inoperative; and means whereby on reaching said inoperative position, said setting means is automatically locked against displacement. 70
15. In a typewriting machine; type keys; a ribbon vibrator; means for actuating the vibrator; and means comprising a rock-shaft and a key-carrying arm thereon for changing the point of connection of the vibrator to its actuator to vary the throw of the vibrator, said key being movable in one direction to increase said throw, and a cam arranged to move the key farther in the same direction and thereby render the actuator inoperative. 75
16. In a typewriting machine; type keys; a ribbon vibrator; means for actuating the vibrator; means comprising a rock shaft and a key-carrying arm thereon for changing the point of connection of the vibrator to its actuator to vary the throw of the vibrator; and a cam engaging said key-carrying arm and operative at will to rock said shaft to a position in which the actuator is rendered inoperative. 80
17. In a typewriting machine; type keys; a ribbon vibrator; means for actuating the vibrator; a key; means actuated by the key for changing the point of connection of the actuator to the vibrator to vary the throw of the latter; a key-setting device operative to move the key into position for rendering the actuator inoperative; and means whereby the actuator when returned from inoperative to operative position by the return of the key-setting device is uniformly set for the same throw of the vibrator. 85
18. In a typewriting machine; a bichrome ribbon vibrator; means to actuate the vibrator comprising a lever, and a toggle connected to the lever; means for setting the toggle for different throws of the vibrator, comprising a pivoted arm in engagement with one end of the toggle; and means for adjusting the angular position of said arm, and thereby shifting the point of connection of the toggle and lever toward and from the fulcrum of the lever. 90
19. In a typewriting machine; a bichrome ribbon vibrator; an actuating lever therefor; a toggle connected to said lever for actuating it; means for setting the toggle for different throws of the vibrator, comprising a pivoted arm in engagement with one end of the toggle; and a key-controlled rock shaft for adjusting the angular position of said arm, and thereby shifting the point of connection of the toggle and lever toward and from the fulcrum of the lever. 95
20. In a typewriting machine; a bichrome ribbon vibrator; a toggle for actuating the same; means for setting the toggle for different throws of the vibrator, comprising a pivoted arm in engagement with the toggle to set the latter in different relations to the vibrator; means for adjusting the angular position of said arm; and a stop on said arm for positively determining the throw of the vibrator to prevent overthrow of the ribbon. 100
21. In a typewriting machine; a bichrome ribbon vibrator; a toggle for actuating the same; means for setting the toggle for different throws of the vibrator, comprising a pivoted arm in engagement with the toggle to set the latter in different relations to the vibrator; means for adjusting the angular position of said arm; and a common support for said toggle and setting arm shiftable between case positions. 105
22. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to the actuator support; and means for swinging said arm with the platen. 110
23. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to the actuator support; and an attachment to the platen-shifting means in engagement with said pivoted arm to swing the latter when the platen is shifted. 115
24. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to the actuator support; and an attachment to the platen-shifting means in pin-and-slot engagement with said pivoted arm to swing the latter when the platen is shifted. 120
25. In a typewriting machine; a platen; means for shifting the same between case positions; a ribbon vibrator; an actuator for

for said vibrator; a support for the actuator; means for shifting the actuator with the platen between case positions, comprising a rigid arm pivoted at one end to the machine frame and pivotally connected at another point to the actuator support; and means for swinging said arm with the platen.

26. In a typewriting machine; a platen; means for shifting the same between case positions; a ribbon vibrator; an actuator for said vibrator, a sliding support for the actuator; means for shifting the actuator with the platen between case positions, comprising an arm pivoted at one end to the machine frame and pivotally connected at another point to the actuator support; and means for swinging said arm with the platen.

27. In a typewriting machine; a platen; means for shifting the same between case positions; a ribbon vibrator; an actuator for said vibrator; a support for the actuator mounted to slide in ways in the machine frame; means for shifting the actuator with the platen between case positions, comprising an arm pivoted at one end to the machine frame and pivotally connected at another point to the actuator support; and means for swinging said arm with the platen.

28. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to the actuator support; means for swinging said arm with the platen; and means for setting the actuator for different throws of the vibrator.

29. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to the actuator support; means for swinging said arm with the platen; means for setting the actuator for different throws of the vibrator; and means for positively preventing overthrow of the ribbon in both case positions.

30. In a typewriting machine; a platen; means for shifting the same between case positions; a ribbon vibrator; an actuator for said vibrator; a support for the actuator; means for shifting the actuator with the platen between case positions, comprising an arm pivoted at one end to the machine frame and pivotally connected at another point to

the actuator support; means for swinging said arm with the platen; means for setting the actuator for different throws of the vibrator; and a stop on said actuator setting means for positively preventing overthrow of the ribbon in both case positions.

31. In a typewriting machine; type bars; a universal bar; a ribbon vibrator; a support for the vibrator; an actuating connection from the universal bar to the vibrator; means for normally limiting the throw of the vibrator, and reacting through said connection and said support to limit the throw of the universal bar; and means for providing an abnormal throw of the universal bar with the vibrator support to permit removal of the type bars.

32. In a typewriting machine; type bars; a universal bar; a ribbon vibrator; a support for the vibrator; an actuating connection from the universal bar to the vibrator; means for normally limiting the throw of the vibrator, and reacting through said connection and said support to limit the throw of the universal bar; and means for providing a shift of the vibrator support from normal position to permit of an abnormal throw of the universal bar, so that the type bars may be removed.

33. In a typewriting machine; type bars; a universal bar; a ribbon vibrator; a support for the vibrator; an actuating connection from the universal bar to the vibrator; means for normally limiting the throw of the vibrator, and reacting through said connection and said support to limit the throw of the universal bar; and means for providing a swing of the vibrator support from normal position to permit of an abnormal throw of the universal bar, so that the type bars may be removed.

34. In a typewriting machine; type bars; a universal bar; a ribbon vibrator; a support for the vibrator; means engaging said support on two sides to hold the same against lateral displacement; an actuating connection from the universal bar to the vibrator; means for normally limiting the throw of the universal bar with said connection; and means for removing the holding means on one side of the vibrator support to permit the latter to be moved and the universal bar to have an abnormal movement, so that the type bars may be removed.

35. In a typewriting machine; type bars; a universal bar; a ribbon vibrator; a support for the vibrator; means engaging said support on two sides to hold the same against lateral displacement, the engaging means on one side of the support being a pivoted plate; an actuating connection from the universal bar to the vibrator; means for normally limiting the throw of the universal bar with said connection; and means for

swinging the holding plate on one side of the vibrator support to permit the latter to be moved and the universal bar to have an abnormal movement, so that the type bars 5 may be removed.

36. In a typewriting machine; type bars; a universal bar; a ribbon vibrator; a support for the vibrator; means engaging said support on two sides to hold the same 10 against lateral displacement; an actuating connection from the universal bar to the vibrator; means for normally limiting the throw of the universal bar with said connection; and means for removing the holding 15 means on one side of the vibrator support to permit the latter to be moved and the universal bar to have an abnormal movement, so that the type bars may be removed, said last-named means being adapted to enable 20 gage and throw the universal bar to its abnormal type bar-releasing position.

37. In a typewriting machine; type bars; a universal bar; a ribbon vibrator; a support for the vibrator; means engaging said support on two sides to hold the same 25 against lateral displacement; an actuating connection from the universal bar to the vibrator; means for normally limiting the throw of the universal bar with said connection; means for removing the holding 30 means on one side of the vibrator support to permit the latter to be moved and the universal bar to have an abnormal movement, so that the type bars may be removed; and 35 a cam on said movable holding means adapted to engage and throw the universal bar to its abnormal type bar-releasing position.

38. In a typewriting machine, the combination of type-bars, a universal bar actuated 40 thereby, a ribbon vibrator, mechanism through which motion is transmitted from the universal bar to the vibrator, a stop to limit the throw of the vibrator and thereby limiting the movement of the universal bar, 45 and means to shift said mechanism into position to permit the universal bar to move beyond said position at which it is arrested by the stop.

39. In a typewriting machine, the combination of type-bars, a universal bar actuated 50 thereby, a ribbon vibrator, mechanism through which motion is transmitted from the universal bar to the vibrator, a stop to limit the throw of the vibrator and thereby limiting the movement of the universal bar, a support on which said mechanism is mounted, said support normally held stationary during the operation of said mechanism, and means to release said support and 55 permit it to move into position to permit movement of the universal bar beyond said position at which it is arrested by the stop.

40. In a typewriting machine, the combination of type-bars, a universal bar actuated 60 thereby, a ribbon vibrator, mechanism

through which motion is transmitted from the universal bar to the vibrator, a stop to limit the throw of the vibrator and thereby limiting the movement of the universal bar, a support on which said mechanism is mounted, 70 and a key operable to swing said support into such position that the universal bar may be moved beyond said position at which it is arrested by the stop.

41. In a typewriting machine, the combination with pivoted type-bars, and a universal bar actuated thereby, said bar normally positioned to prevent removal of the type-bars from their fulcrum, of a ribbon vibrator, mechanism through which motion 80 is transmitted from the universal bar to the vibrator, a stop to limit the throw of the vibrator and thereby limit the movement of the universal bar, a support on which said mechanism is mounted, and means to release 85 said support and permit it to shift to a position such that said stop will permit the universal bar to be moved beyond said limit, to such position that the type-bars are free to be removed from their fulcrum. 90

42. In a front-strike typewriting machine, the combination with a platen shiftable up and down to upper and lower case positions, of pivoted type-bars arranged to swing upwardly and rearwardly about their fulcrum 95 to print at the platen, a universal bar moved rearwardly by the type-bars, a ribbon vibrator, connecting mechanism between the universal bar and said vibrator for actuating the latter, a support on which said 100 mechanism is mounted, said support connected to shift up and down with the platen, a stop to limit the throw of the vibrator and also limiting the movement of the universal bar by the type-bars, said universal 105 bar normally overlying a portion of the type-bars and preventing their removal from their fulcrum rod, and means whereby said support may be swung rearwardly from its normal position and thereby permit an 110 abnormal rearward movement of the universal bar into position to release the type-bars and permit their removal.

43. In a typewriting machine, the combination with a ribbon vibrator, of type keys, 115 means for actuating the vibrator from the type keys, said means comprising a toggle connected at one end with the vibrator and a universal bar to actuate the toggle, and means to vary the throw of the vibrator, 120 said last-mentioned means comprising mechanism to shift the point of connection of the toggle with the vibrator into position to vary the angle between the toggle arms and thereby vary the extent of movement imparted to the vibrator by a given movement of the universal bar. 125

44. In a typewriting machine, the combination with a universal bar, of a ribbon vibrator, mechanism between said bar and 130

vibrator for actuating the latter from said bar, said mechanism comprising a vibrator lever and a toggle having the outer end of one arm connected to said lever, and means

5 to swing said arm to adjust the point of connection of the toggle and lever toward and from the fulcrum of the lever while the other arm of the toggle remains at rest, thereby varying the throw of the vibrator

by varying the angle between the toggle 10 arms and by varying the distance of said point of connection from the fulcrum of the lever.
